CIRCUIT BREAKER

Robert C. Dickinson, Wilkinsburg, Pa., assignor
to Westinghouse Electric & Manufacturing
Company, East Pittsburgh, Pa., a corporation
of Pennsylvania

Application May 31, 1938, Serial No. 210,971

10 Claims. (Cl. 200—146)

The invention relates to circuit breakers in general and more particularly to contact means or systems for air circuit breakers of the high-voltage type.

Heretofore, it has been the usual practice to provide high-voltage air circuit breakers with a contact means for each pole comprising a movable contact arm pivoted at its lower end and carrying the main and arcing movable contacts at its free end for engaging the stationary main and arcing contacts. The pivotal mounting of the contact arm made it necessary to provide a flexible shunt conductor of full load carrying capacity for connecting the movable contacts to the lower terminal of the breaker. Flexibility of the contact means for predetermining the contact pressure was obtained by pivotally mounting the stationary contact and biasing it towards the movable contact by means of a spring. The pivotal mounting of the stationary contact required the provision of a second flexible shunt conductor also of full load carrying capacity for connecting the stationary contact to the upper terminal of the breaker.

A contact system of the type described above, while fairly satisfactory as to operation, has a number of disadvantages. The number of moving parts of the system are excessive and the current carrying flexible shunts are large and subject to deterioration. In general, the system is complicated and expensive to manufacture.

An object of the invention is the provision of a circuit breaker embodying an improved contact system which does not require any full load carrying capacity flexible shunts for connecting the contacts to the terminals of the breaker.

Another object of the invention is the provision of an improved contact system for an air circuit breaker as described in the preceding paragraph in which the stationary contacts are rigidly mounted and the movable contact assemblage carries a means for providing the required contact pressure.

Another object of the invention is the provision of an improved contact system as described above in which the movable contact is caused to roll on the stationary contact during circuit interruption so that only the arcing tips of the contacts are in engagement immediately before separation of the contacts.

Another object of the invention is the provision of an improved contact system, as described in the preceding objects, which is simple, has relatively few moving parts, and which is inexpensive to manufacture.

The novel features that are considered characteristic of the invention are set forth in particular in the appended claims. The invention itself, however, both as to structure and operation, together with additional objects and advantages thereof, will be best understood from the following detailed description of a preferred embodiment thereof when read in conjunction with the accompanying drawings, in which:

10 Figure 1 is a fragmentary side elevational view, partly in section, of a circuit breaker embodying a contact system constructed in accordance with the invention, the contacts being shown in the closed position;

15 Fig. 2 is a view similar to Fig. 1 showing the contact system in the partly open position immediately following a tripping operation of the breaker;

20 Fig. 3 is a view similar to Fig. 1 showing the contact system in the full open position; and

Fig. 4 is an enlarged sectional view taken substantially along the line IV—IV of Fig. 1 showing the connection of the operating rod to the switch arm and the mounting of the contact

25 bridging bar.

In the accompanying drawings, only those parts of the circuit breaker are shown which are considered necessary for a complete understanding of the invention.

30 Referring to the drawings, the reference numeral 5 designates a portion of a fabricated steel frame which serves to support the circuit breaker. A pair of insulating bushings 7 and 9 of strong insulating material extend through spaced openings provided therefor in the frame 5, and are rigidly secured to the frame by means of the flanges 11 carried by the bushings and the bolts 13. The bushings 7 and 9 serve to support a pair of spaced rigid terminal conductors 15 and 17 which extend through the bushings and are insulated from the frame 5 thereby. These spaced terminal conductors 15 and 17 form the two terminals of the breaker.

45 A pair of stationary contact members 19 and 21 are rigidly mounted on the ends of the terminal conductors 15 and 17, and these contact members are adapted to be connected in the circuit controlled by the breaker by means of suitable terminal connections (not shown) at

50 the opposite ends of the terminal members 15 and 17. The upper contact member 19 which forms the stationary arcing contact of the breaker is provided with an arcing tip 23 of suitable arc resisting material. The lower contact member 21 has a yoke-shaped extension 25 rigidly

secured thereto which serves to pivotally support a movable contact assemblage indicated generally at 27.

The movable contact assemblage comprises a U-shaped switch member 29 which is pivotally mounted on the extension 25 of the contact member 21, and a bridging contact arm 31 of conducting material which is connected intermediate its ends to the switch member 29. The switch member 29 has a pair of spaced parallel side walls 33 connected by a transverse bight portion 35 which is provided with a semi-circular extension 37 having an inwardly extending edge 39. The extension 37 serves as a seat for one end of a spring means which will hereinafter be described. The switch member 29 is pivotally mounted on the extension 25 of the contact member 21 by means of a pivot pin 41 which extends through aligned openings provided therefor in the legs of the extension 25 and in the lower ends of the side walls 33 of the switch member 29.

An operating rod 43 of strong insulating material has one of its ends pivotally connected to the switch member 29 by a yoke 45 (Fig. 4) secured to the end of the rod. The yoke 45 extends between and engages the inner ends of the side walls 33 of the switch member 29 and is pivotally connected to the switch member by means of a pivot pin 47, which extends through aligned openings in the legs of the yoke 45 and in the side walls of the switch member 29. The opposite end of the operating rod 43 is pivotally connected to a crank arm 49 secured to a rotatable operating shaft 51. The shaft 51 has cylindrical ends which are rotatably mounted in a pair of bearings 53 carried by the frame 5, and a square portion 55 on which the crank arm 49 is mounted.

An operating crank 57 is also secured to the square portion 55 of the shaft 51, and this crank is adapted to be connected to a suitable operating mechanism (not shown) for moving the switch member 29 to open and to closed circuit positions. The operating mechanism is not an important part of the present invention, and any standard mechanism of the type embodying an opening spring for biasing the switch member to open position, a closing means for moving the switch member to closed position, and a suitable tripping means for causing opening movement of the switch member may be used. One suitable form of operating mechanism which may be connected to the operating crank 57 for moving the switch member 29 to open and closed position is that disclosed in Patent No. 1,807,020, issued to R. C. Van Sickle, May 26, 1931, and assigned to the assignee of the present invention.

The contact arm 31 which is of conducting material serves to bridge the stationary contact members 19 and 21 in the closed position of the breaker to establish an electrical circuit therebetween, and is movable to open and closed circuit position by the opening and closing movement of the switch member 29. The contact arm 31 is provided at its upper end with a movable arcing contact 59 for engaging the stationary arcing contact member 19, and at its opposite end with a movable contact 61 for engaging the stationary contact member 21. The movable arcing contact 59 is provided with an arcing tip 63 of arc resisting material for cooperating with the arcing tip 23 of the contact member 19 during opening of the breaker.

The contact arm 31 is disposed between the legs of the yoke 45 and also between the side walls 33 of the switch member 29, and is connected to the

switch member by a pin-and-slot connection comprising the pivot pin 47 and a slot 65 formed in the arm 31, which engages the pin 47. A pair of washers 67 (Fig. 4) are interposed between the sides of the contact arm 31 and the legs of the yoke 45 to prevent lateral displacement of the contact arm 31 during operation of the switch member.

A spring means 69, comprising a pair of concentric coil springs 71 and 73, is interposed between the semi-circular extension 37 of the switch arm 29 and the contact arm 31. The right-hand end of the spring means 69 seats against the semi-circular extension 37 of the switch arm 29 and the left-hand end engages a seat 75 secured to the contact arm 31 at a point intermediate the connecting pin 47 and the arcing contact 59. Lateral displacement of the springs 71 and 73 is prevented by a pair of studs 77 and 79 carried by the switch member 29 and the contact arm 31, respectively. The spring means 69 serves to provide a predetermined contact pressure between the movable contacts 59 and 61 and their cooperating stationary contact members 19 and 21 when the breaker is in closed circuit position, and also causes the contact arm 31 to first separate from the lower stationary contact member 21 and simultaneously rock on the arcing contact member 29 during the initial portion of the opening movement of the switch member 29, so that only the arcing tips 23 and 63 remain in engagement prior to movement of the contact arm 31 to open circuit position.

An adjusting screw 81 is threaded through the lower end of the bight portion 35 of the switch member 29 for engaging the lower end of the contact arm 31 to limit the rocking movement of the arm as it rocks on the arcing contact member 19 during the initial portion of the opening movement of the switch member 29, as shown in Fig. 2.

A relatively small flexible shunt conductor 83 electrically connects the lower stationary contact member 21 to the contact arm 31 to maintain the circuit between the lower contact member 21 and the contact arm 31 during circuit interruption. The shunt conductor 83 need only be of relatively small cross-section sufficient to carry the current momentarily while the breaker is opening the circuit, since when the breaker is closed the current flows directly from the stationary contact member 21 to the contact arm 31 through the movable contact 61. The purpose of the shunt conductor 83 is to shunt the current around the contacts 21 and 61 when these contacts separate during opening of the breaker until the circuit is finally interrupted by opening of the arcing contacts 23 and 63. Thus the shunt 83 prevents any arc between the contacts 21 and 61 during opening or closing of the breaker.

By providing two solid stationary contacts connected respectively to the terminals of the breaker, and a solid bridging contact which is moved in the manner disclosing, the necessity of additional resiliently mounted arcing contacts and full load carrying capacity shunts has been eliminated. The shunt 83 which connects the lower stationary contact 21 to the movable bridging contact 33 can be of relatively small size or cross-section as it only carries the current momentarily during separation of the upper contacts, the contacts 21 and 61 serving to carry full load current when the breaker is closed. The purpose of the flexible shunt conductor 83 is

to prevent arcing from taking place between the contacts 21 and 61, and the purpose of the contacts 21 and 61 is to eliminate the necessity of providing a flexible shunt conductor of full load carrying capacity to carry the current continuously.

An arc extinguishing structure of any suitable type may be associated with the arcing contacts 19 and 69 of the breaker for extinguishing the arc drawn between these contacts during circuit interruption. One form of arc extinguishing structure which may be associated with the arcing contacts of the breaker is that disclosed and claimed in Patent No. 2,080,611, issued to F. B. Johnson, May 18, 1937, and assigned to the 15 assignee of the present invention.

The operation of the circuit breaker is briefly as follows: When the breaker is in closed circuit position, as shown in Fig. 1, the latch of the operating mechanism (not shown) releasably holds the operating rod 43 and the switch member 28 in closed position, as shown in Fig. 1, against the force exerted by the breaker opening spring and the spring means 69, which is held in compression. In this position it will be noted that the 25 connecting pin 47 is disposed intermediate the ends of the slot 65 since the switch member 28 has been moved slightly beyond the position necessary to cause the contact arm 31 to bridge the stationary contact members 19 and 21. This position of the switch member 28 causes the spring 69 to be compressed and the reactive force of the springs 71 and 73 of the spring means 69 acting on the contact arm 31 provides a predetermined contact pressure of the contacts 69 and 61 on the stationary contact members 19 and 21.

When the breaker is tripped, the operating rod 43 is moved towards the right by the force exerted on the operating crank 57 by the opening spring of the breaker mechanism. The opening movement of the operating rod 43 and the reactive force of the spring means 69 causes the contact arm 31 to rock on the upper stationary contact member 19 to the position shown in Fig. 2, in which the movable contact 61 is separated from the lower stationary contact member 21, and only the arcing tips 23 and 63 of the upper pair of contacts remain in engagement. This rocking movement of the contact arm 31 is limited by the adjustable stop screw 81. The continued opening movement of the operating rod 43 causes the contact arm 31 to be moved by the switch member 28 to the open circuit position shown in Fig. 3. Since the arcing tips 23 and 63 are the last portions of the contact system to separate during opening of the breaker, the arc formed during circuit interruption is drawn only between these arcing tips.

In closing the breaker, substantially the reverse action takes place. The operating rod 43 is moved towards the left by the operating mechanism of the breaker to cause the switch member 28 to be rotated in a counter-clockwise direction about the pivot pin 41. During the movement of the switch member 28 toward the circuit closing position, the contact arm 31 is moved with the switch member but remains in the canted position relative to the switch arm, as shown in Fig. 3, by reason of the force exerted by the spring means 69, so that the arcing tips 23 and 63 are 70 the first portions of the contact system to be brought into engagement. The continued closing movement of the operating rod 43 following engagement of the arcing tips 23 and 63 causes the contact arm 31 to be rocked on the station-

ary contact member 19 in a clockwise direction until the movable contact 61 engages the lower stationary contact member 21. A slight further closing movement of the operating rod 43 before it is latched in closed position by the operating mechanism compresses the spring means 69 to provide a predetermined contact pressure between both sets of movable and stationary contacts of the circuit breaker.

10 It will thus be seen that the invention provides a simple and improved contact system for a circuit breaker which eliminates the necessity of any full-load carrying capacity shunts, and in which the means for providing contact pressure is entirely carried by the movable contact assemblage.

The current path through the breaker when the breaker is in closed position passes entirely through rigid conducting members and rigidly 20 mounted contacts, thus producing a much more efficient and desirable contact system than the contact systems of the prior art devices which embodied resilient conducting members and contacts.

25 While the invention has been disclosed in accordance with the provisions of the patent statutes, it is to be understood that various changes in the structural details thereof may be made without departing from the spirit of the invention. It is desired, therefore, that the appended claims be given the broadest reasonable construction permissible in the light of the prior art.

I claim as my invention:

30 1. In a circuit breaker, a pair of rigidly mounted stationary contacts, a movable contact member of rigid conducting material for bridging said contacts, means for moving said member to first cause said member to separate from one of said contacts and then to separate from the other of said contacts, and means electrically connecting said contact member to the stationary contact from which it first separates providing a low resistance electrical connection therebetween.

35 2. In a circuit breaker, a pair of spaced rigidly mounted stationary contacts of rigid conducting material, a movable contact bar of rigid conducting material for bridging said contacts to establish a circuit therebetween, means for moving said contact bar to open and to closed circuit position, said means being operable during an opening operation to cause said contact bar to first separate from one of said contacts and then to separate from the other of said contacts, and 40 50 55 a flexible shunt conductor connecting said bar to the contact from which it first separates providing a low resistance electrical connection therebetween.

60 3. In a circuit breaker, a pair of rigidly mounted stationary contacts, a movable contact arm for bridging said contacts to establish a circuit therebetween, means for moving said contact arm to open and to closed circuit position, said means being operable during an opening operation to cause said arm to first separate from one of said contacts and simultaneously rock on the other of said contacts so as to engage only the tip portion thereof, and then to separate from said last mentioned contact, and a conductor electrically connecting said arm to the contact from which it first separates providing a low resistance electrical connection therebetween.

65 4. In a circuit breaker, a pair of rigidly mounted stationary butt contacts, a movable

contact arm for bridging said contacts to establish a circuit therebetween, means for moving said contact arm to open and to closed circuit position, said means being operable during an opening operation to cause said arm to first separate from one of said contacts and simultaneously rock on the other of said contacts so as to engage only the tip portion thereof, and then to separate from said last mentioned contact, and a flexible shunt conductor connecting said arm to the contact from which it first separates providing a low resistance electrical connection therebetween, said means for moving said arm including yielding means for providing a predetermined contact pressure of said arm on said contacts.

5. In a circuit breaker, a pair of rigidly mounted stationary butt contacts, means for establishing and interrupting a circuit between said contacts comprising a movable switch arm, a movable bar of rigid conducting material for bridging said contacts movable with said arm and movable relative thereto, yielding means interposed between said bar and said switch arm for providing a predetermined contact pressure between said bar and said contacts when the breaker is closed and for causing said bar to first separate from one of said contacts and then to separate from the other contact during opening movement of said switch arm, and a shunt conductor connecting said bar to the stationary contact from which it first separates providing a low resistance electrical connection therebetween.

6. In a circuit breaker, a pair of rigidly mounted stationary butt contacts, a movable contact arm for bridging said contacts, means for moving said arm to open and to closed circuit position comprising a movable switch arm, a spring interposed between said contact arm and said switch arm for providing a predetermined contact pressure between said contact arm and said contacts when the breaker is closed and for causing said contact arm to separate from one of said contacts and simultaneously rock on the other contact so as to engage only the tip portion thereof before separating from said last mentioned contact during opening movement of said switch arm; and a flexible shunt conductor connecting said contact arm to the stationary contact from which it first separates providing a low resistance electrical connection therebetween.

7. In a circuit breaker, a pair of rigidly mounted stationary butt contacts, a movable contact arm of rigid conducting material for bridging said contacts to establish a circuit therebetween, a movable switch arm for moving said contact arm to open and to closed circuit position, said contact arm being connected intermediate its ends to said switch arm by a pin and slot connection, a spring interposed between said contact arm and said switch arm for providing a predetermined contact pressure between said contact arm and said contacts when the breaker is closed and for causing said contact arm to first separate from one of said contacts and simultaneously rock on the other of said contacts so as to engage only the tip portion of said last mentioned contact before separating therefrom during opening movement of said switch arm, and a shunt conductor connecting said contact arm to

70 the stationary contact from which it first separates, providing a low resistance electrical connection therebetween.

8. In a circuit breaker, a pair of spaced terminal members, a pair of spaced rigid stationary contacts connected respectively to said terminal members, one of said stationary contacts having an arcing contact portion, a movable contact arm of rigid material for bridging said stationary contacts to complete a circuit between said terminal members, and means for moving said contact arm to cause said arm to first separate from one of said contacts and then to separate from the contact having the arcing contact portion, and conducting means of low electrical resistance connecting said arm to said one contact.

9. In a circuit breaker, a pair of spaced terminals, a pair of spaced rigidly mounted stationary contacts connected respectively to said terminals, one of said contacts having an arcing contact portion, a movable contact arm for bridging said contacts to establish a circuit between said terminals, said arm rigidly carrying a pair of contacts for engaging said stationary contacts, one of the movable contacts carried by said arm having an arcing contact portion for cooperating with the arcing contact portion of the stationary contact, means for moving said arm to open and to closed circuit position, said means being operable during an opening operation to first cause one of the movable contacts to separate from its stationary contact and to cause only the arcing contact portions of the other contacts to engage, and then to cause the other movable contact having the arcing contact portion to separate from the stationary contact having the arcing contact portion, yielding means for providing a predetermined pressure engagement of said contacts when the breaker is closed, and means providing a low resistance electrical connection between said contact arm and the stationary contact from which it first separates for causing an arc to be drawn only between arcing contact portions of the stationary and movable contacts so equipped, during a circuit opening operation.

10. In a circuit breaker, a pair of spaced terminals, a pair of rigidly mounted stationary butt contacts connected respectively to said terminals, one of said contacts having a rigid arcing tip, movable contact means comprising a contact arm of rigid conducting material for bridging said contacts to complete a circuit between said terminals, said arm rigidly carrying a pair of movable butt contacts for engaging said stationary contacts, means for moving said arm to first cause one of said movable contacts to separate from its cooperating stationary contact and the other movable contact to simultaneously rock on its cooperating stationary contact which has the arcing tip so that only the tip portions of said last mentioned contacts engage, and to then cause movement of both of said contacts to an open circuit position away from said stationary contacts, and conducting means electrically connecting said contact arm to the stationary contact from which it first separates providing a low resistance electrical connection therebetween.

ROBERT C. DICKINSON.
